CLAIM

The ornamental design for a beer flight, as shown and described.

DESCRIPTION

FIG. 1 is a top plan view of a beer flight showing the new design;

FIG. 2 is a bottom plan view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top-front-left perspective view thereof;

FIG. 8 is a bottom-rear-left perspective view thereof; and, FIG. 9 is a top-front-left perspective view of the beer flight with the glass holder portion disconnected.

The equal length broken lines depict portions of the beer flight that form no part of the claimed design.

The interior of the beer flight, delineated by the equal-length broken lines and the interior left-side lid ledge shown in FIG. 9, as well as their mirrored counterparts not shown in FIG. 9, forms no part of the claimed design. The appearance of any portion of the beer flight between equal-length broken lines forms no part of the claimed design.
